UNITED STATES PATENT OFFICE.

WILLIAM L. R. EMMET AND EDWARD M. HEWLETT, OF SCHENECTADY, NEW YORK, ASSIGNORS TO GENERAL ELECTRIC COMPANY, A CORPORATION OF NEW YORK.

HIGH-POTENTIAL SWITCH.

SPECIFICATION forming part of Letters Patent No. 789,597, dated May 9, 1905.

Application filed February 14, 1901. Renewed January 11, 1905. Serial No. 240,574.

To all whom it may concern:

Be it known that we, WILLIAM L. R. EMMET and EDWARD M. HEWLETT, citizens of the United States, and residents of Schenectady, county of Schenectady, State of New York, have invented certain new and useful Improvements in High-Potential Switches, of which the following is a specification.

This invention relates to high-potential switches or circuit-breakers of the oil-break type, in which the circuit is ruptured at contact-points under an insulating fluid. In the construction of switches of this type oil is commonly employed as the medium in which the circuit is opened and is well adapted for the purpose, both on account of its high insulating properties and by reason of its liquid character, by reason of which it closes in around the points of contact across the arc and serves to condense and mechanically displace the arc-vapors and fill the space with a medium of high insulating power. The employment of oil, however, is accompanied by some disadvantages, one of which is the carbonization of the oil and the deposit of soot on the terminals and adjacent parts. When the circuit is opened, the small arc formed reduces some of the oil, setting free the basic carbon in the form of fine particles, which float in the oil and gradually agglomerate and form deposits on the terminals and adjacent parts, which unless removed interfere with the operation of the switch.

It is the object of one part of our invention to avoid this difficulty, to which end we proceed by mounting the movable element of the switch or circuit-breaker so that in opening the circuit it takes a downward movement in the oil, thereby effecting the contact on the under surface of the fixed terminal, which will be rendered self-cleaning by the engagement of the parts and from which the carbon will fall and settle in the bottom of the containing vessel. Another advantage incidental to this organization is that by reason of the downward movement of the movable contact the arc lengthens or is stretched

through a progressively-increasing depth of liquid, thereby subjecting the arc stream to an increasing pressure and also giving the insulating vapors developed a longer path to travel in the cool liquid before reaching the air. This results in a decreased fire hazard, since it sometimes happens that the vapors liberated by the heat of the arc escape in sufficient volume to reach the top of the containing vessel and may be ignited there. A further improved action follows from the fact that the contact is made in the upper part of the oil-bath, which is cleaner than the lower parts, as the carbon and other foreign matter settles toward the bottom. We effect also an improved action of the oil at the points of contact by constructing the movable terminal so as to create as little disturbance of the oil as possible. Eddy-currents in the body of the oil are apt to render irregular the flow of liquid across the arc stream in the act of extinguishment. We find that by shaping the movable element so that it presents a symmetrical tapering edge in the direction of its movement in the oil it cleaves the latter more readily and by preventing eddies, or at least rendering them uniform, permits the oil to close in around the surface of rupture uniformly. Our invention comprises also improved means for operating the switch, by means of which a compact organization is provided and safety of operation assured. We provide a system of bell-crank levers for raising and lowering the contacts and a toggle which may be cramped when the contacts are set in engagement, placing them in tight fixed relation to one another.

The several features of novelty will be more particularly pointed out hereinafter and will be definitely indicated in the appended claims.

In the accompanying drawings, which illustrate our invention, Figure 1 is a sectional view of a switch or circuit-breaker embodying our improvements, and Fig. 2 is a sectional view on a plane at right angles to that shown in Fig. 1.

The type of switch shown in the drawings

is one adapted for mounting on a switch-board. It comprises an oil-tank 1, formed of galvanized sheet-iron and having overlapping joints riveted and soldered to make them fluid-tight, across which are run a series of wooden partitions 2 2^a, dividing the tank into a plurality of independent compartments for the several contacts. The tank is lined with wood or other insulating material, as indicated. The partitions 2 2^a not only form independent oil-chambers for the contacts, but act as barriers to prevent an arc from striking across from one contact to another. The fixed terminals of the circuit are mounted in a cast-metal cover 3, which is provided with an extension 3^a, forming a support for the controlling-levers and to permit its attachment to the rear of the switch-board 4. The fixed terminals are mounted 20 in porcelain bushings 5 6 7 5^a, &c., which may be firmly seated in the cover by a lead joint, as indicated at 8. The bushing is recessed at both ends, the upper end forming a socket for a lead from the high-potential circuit, which is led through it without removing its insulating compound or braiding, as seen in Fig. 2. To the bared end of one of these cables is secured a copper or phosphor-bronze rod 9, the underside of which is threaded and adapted to receive the contact-clip 10, 11, or 12. After the latter are screwed firmly home the free space around the cable is filled with an insulating compound containing asphaltum or other material which 30 will adhere to the walls of the porcelain and which will form a good joint with the compound with which the braiding of the conductor is saturated. Thus all metallic parts are deeply embedded beneath the surface 40 of a rigid insulating compound, which prevents the entrance of moisture, and the tendency of current to jump through the air if the latter is moist is greatly reduced, since before doing so it must break down the solid dielectric, which is impervious to moisture. The insulating-bushings are made sufficiently long to dip well into the oil-bath in the several compartments, the oil-level being indicated in the drawings. No claim is here- 50 made to the specific means for insulating the terminals, as it is covered in an application in the name of Charles C. Badeau. The fixed contact-clips 10 11 12 are arranged in pairs, one pair of which may be placed in each compartment. These clips are formed 55 of a solid block of brass or phosphor-bronze, which forms the terminal and upon which are riveted four or more yielding spring-contacts of phosphor-bronze, as indicated in the drawings, to which may be attached arcing shoes or tips 13.

The switch shown in the drawings is adapted for triphase alternating currents. This, however, is shown merely by way of example, since our improvements are applicable

to high-potential currents of any kind whatever. The switch shown, therefore, is of the triple-pole double-break type, two breaking-points in each limb of the triphase circuit being provided. As will be evident from Fig. 70 2, the contacts are arranged in pairs, each pair of contacts being bridged or adapted to be bridged by a brass conductor 14. This conductor is mounted on the end of the wooden rod 15, the several rods being 75 screwed into a common casting, to which is attached a bell-crank lever 16. The frame carrying the wooden rods is connected to the bell-crank lever 16 by a loose joint, and slots are provided, as indicated at 17, to permit 80 the rods to yield laterally in their bearings when the bell-crank lever is raised or lowered. The lever 16 is pivoted on a part of the cover at a point 18 about midway between the upper and lower limits of movement of the 85 swinging end. Connected to the other crank of the lever 16 is a link 19, to which is pivoted a bell-crank lever 20, controlled by an operating-handle 21 on the front of the board through the link 24. The link 19 and the co-operating arm of the bell-crank lever 20 are so arranged that they form a toggle, as indicated in Fig. 1, which when the operating-lever 21 is forced home (the position indicated in Fig. 1) is cramped off center, thereby locking the parts in a position where the switch is closed. A stop 22 limits the movement of the operating-lever. The length of the levers in the operating system is so regulated that they do not strike one another in the several ranges of movement. The movable bridging contacts 14, &c., are provided at the top with a frusto-pyramidal contact adapted to slide into engagement with the shoes of the fixed contact-clips on the four sides, as indicated in Figs. 1 and 2, and the lower sides of the bridges are tapered or otherwise shaped so as to gently and symmetrically displace the liquid when the switch is lowered in opening the circuit. We have shown this bridging-contact as having a pointed nose which shears the liquid somewhat after the fashion of the bow of a boat and prevents any violent disturbance on the liquid. The cover may be bolted firmly to the tank by bolts 110 engaging ears on the tank and cover, respectively, as seen in Figs. 1 and 2, and the tank may be provided with handles 23 23^a to facilitate its removal from the attached parts for change of oil or other attention. 115

A switch as thus constructed does not foul at the contacts with deposits of carbon, since the closing-and-opening action scrapes off from the lower sides of the fixed contact the deposits of carbon, which drop to the bottom 120 of the vessel, and the smooth faces of the terminal supports permit easy cleansing in case of small deposits. Such a switch has proven effective for extremely high voltages over a 125 long period of service.

What we claim as new, and desire to secure by Letters Patent of the United States, is—

1. A high-potential switch for electric currents comprising an oil-chamber in which the contacts are opened and closed beneath the surface of the oil, an insulating-support for the fixed contacts, and means for shifting the movable contacts in the oil downwardly from the fixed contacts when opening the circuit, and upwardly into engagement with said fixed contacts when closing the circuit.
2. A high-potential switch for electric currents, comprising an oil-chamber, and circuit making and breaking contacts beneath the surface of the oil in said chamber, the movable contacts being shaped to symmetrically displace the oil with relation to the arc formed at the point of rupture.
3. A high-potential switch, comprising an oil-chamber containing the circuit making and breaking contacts beneath the surface of the oil, means for separating the contacts, and means for preventing irregular oil-eddies at the point of rupture.
4. A high-potential switch comprising an oil-chamber, contacts for making and breaking the circuit beneath the oil in the chamber, the movable contact being provided with a cutting edge to cleave the oil in the direction of opening the circuit.
5. A high-potential switch having fixed contacts, an oil-bath submerging the same, a cover for the vessel containing the oil, hollow insulators supported thereby for the fixed contacts, and movable contacts for making and breaking the circuit guided by said cover.
6. A high-potential switch for electric currents, comprising an oil-chamber, fixed contacts supported therein beneath the oil-level and insulated therefrom, a metallic bridge for coupling the contacts, an insulating-rod extending outside the oil-chamber and connected to the bridge, an operating-handle for raising and lowering the rod, and a toggle for cramping the switch in its closed position.
7. A high-potential switch for electric currents, comprising a chamber containing an insulating liquid, circuit making and breaking contacts beneath the liquid surface, a reciprocal movable contact, and means for drawing the arc, in rupturing the circuit, downwardly in the liquid.
8. A high-potential switch for electric currents, comprising a chamber containing an

insulating liquid, fixed terminals beneath the surface of the liquid having the contact-surface toward the bottom, a movable contact device, and means for shifting it downwardly from the fixed contacts in opening the circuit and upwardly over the same path in closing the circuit.

9. A high-potential switch for electric currents, comprising a chamber containing an insulating liquid, a plurality of fixed contacts beneath the liquid-level facing the bottom, a bridging-contact, an insulating-rod carrying the same extending outside of the liquid, and an operating device for raising and lowering the rod.

10. A high-potential switch for electric currents, comprising an oil-chamber, fixed contacts beneath the oil, movable contacts, guides for the same, levers for raising and lowering said contacts, a toggle to lock the switch closed, and means for cramping and collapsing the toggle.

11. A high-potential switch for electric currents, comprising an oil-chamber, fixed contacts beneath the oil-level, composed of a plurality of yielding metal fingers projecting downwardly, and a vertically-movable contact adapted to wedge apart said fingers by an upward movement.

12. A high-potential switch for electric currents, comprising an oil-chamber, fixed contacts beneath the oil-level each composed of a plurality of yielding metal fingers, and a movable contact to engage the fingers shifting downwardly to break the circuit.

13. A high-potential switch for electric currents, comprising an oil-chamber, separable contacts beneath the oil-level composed of a plurality of spring-fingers, arcing-tips on said fingers, and a downwardly-moving contact co-operating therewith.

14. A high-potential switch for polyphase currents, comprising an oil-chamber, a plurality of fixed terminals for each phase, movable bridging-contacts, insulating-rods carrying the same, and means for lowering said rods to open all phases simultaneously by a downward-break.

In witness whereof we have hereunto set our hands this 12th day of February, 1901.
